SET OF PLAYING CARDS

Yvonne Matthews, New York, N. Y.

Application June 7, 1952, Serial No. 20,071

Term of patent 14 years

(Cl. D34—13)

To all whom it may concern:

Be it known, that Yvonne Matthews, a citizen of United States of America residing at New York city, in the county of New York and State of New York, has invented a new, original, and ornamental Design for a Set of Playing Cards, of which the following is a specification, reference being had to the accompanying drawing, forming part thereof.

The single figure is a face view of 16 cards representative of the 52 cards in a set of playing cards, showing my new design.

The figure shows 4 cards from each of the 13-card suits in the set, and includes cards representative of the rank of King, Queen, Jack, Ace, and cards numbered from 10 to 2 which constitute each suit.

The remaining cards in each suit, not shown,

differ from those shown only in the rank denominating letter or numeral positioned outermost in the corner boxes and centrally located in the pip.

The cards are shaded to show color contrast, are of conventional thickness, and the backs thereof are plain or conventional.

I claim:

The ornamental design for a set of playing cards, as shown and described.

YVONNE MATTHEWS.
